United States Patent Office

Des. 232,202
Patented July 30, 1974

232,202

SEAT BASE OR SIMILAR ARTICLE

Hugh C. Acton, Ross Township, Kalamazoo County, Mich., assignor to The Vecta Group, Inc., Kalamazoo, Mich.

Continuation-in-part of design application Ser. No. 23,048, May 18, 1970. This application Mar. 27, 1972, Ser. No. 238,721

Term of patent 14 years

The portion of the term of the patent subsequent to Oct. 3, 1986, has been disclaimed

Int. Cl. D6—06
U.S. Cl. D6—196

Fig. 1

Fig. 2

Fig. 3

Fig. 4

Fig. 5

Fig. 6

FIG. 1 is a perspective view of a seat base or similar article embodying my new design;

FIG. 2 is a front elevational view thereof;

FIG. 3 is a bottom view thereof;

FIG. 4 is a side view thereof;

FIG. 5 is a perspective view of a modified seat base or similar article;

FIG. 6 is a bottom view thereof;

FIG. 7 is a side view thereof;

FIG. 8 is a perspective view of a further modified seat base or similar article; and

FIG. 9 is a bottom view thereof.

This application is a continuation in part of design patent application Ser. No. 23,048 filed May 18, 1970, and entitled seat base.

I claim:

The ornamental design for a seat base or similar article, as shown.
